DYEING APPARATUS FOR TEXTILES

Ernest A. Stienen, New York, N. Y.

Application June 24, 1938, Serial No. 215,537

2 Claims. (Cl. 68—187)

This invention relates to a dyeing apparatus for textiles.

The object of the invention is the production of a dyeing apparatus in which the objects to be dyed, as for example hosiery, hats, caps and various other articles are packed one over the other and maintained in place against one another to prevent any friction between them.

The second object of the invention is the production of a dyeing apparatus, in which the articles dyed are always immersed in the dye liquor during the operation of dyeing.

The third object of the invention is the production of a dyeing apparatus, in which the articles dyed are subjected to pressure on their top and bottom, with a rapid circulation of dye liquor through the same, to subject the articles treated to the action of the dye liquor before the color of the latter is exhausted.

The fourth object of the invention is the production of dyeing apparatus provided with a basket for holding the articles treated in place, said basket provided with a cover which can be maintained at different levels to vary the capacity of the basket.

The fifth object of the invention is the production of dyeing apparatus with a basket for holding the articles treated and comprising a pair of members which are detachably locked and hinged in place, and which covers can be swung open for inspecting and testing the articles operated upon and also for packing or unloading said articles from the basket.

Other objects will be apparent from the specifications, drawings and claims hereinafter set forth.

In the drawings Fig. 1 represents a front view of the apparatus for dyeing the objects to be dyed; Fig. 2 shows a top view of Fig. 1, partly broken away; Fig. 3 indicates a section of Fig. 2, on the line 3—3, with portions in full lines; Fig. 4 represents a section of Fig. 2 on the line 4—4 with portions in full lines, and Fig. 5 is an enlarged fragmentary portion of Fig. 3.

The dyeing apparatus comprises the oblong conical shaped dye liquor reversing container designated in its entirety by the numeral 20. The container 20 is indicated having the conical shaped wall 21 at its upper end, is shown with the flange 22. Legs 24 are connected to the lower face of the flange 22 by means of angle irons 25, and at the lower ends of said legs are indicated the angle irons 26, which latter are connected to the supporting platform or base 28. The container 20 has indicated the cross wall

30 with the upper portion 31, and the cross walls 32. The cylindrical wall 33 connects the walls 32. The container 20 has extending therethrough the opening 32a which is located above the cylindrical wall 33. The wall 30 has integral therewith the cylindrical shaped propeller housing 38.

The wall 30 divides the container 20 into the chambers 49 and 41. The wall 21 of the container 20 has connected thereto a pair of stuffing boxes 43. A propeller shaft 44 extends through the stuffing boxes 43, and through the axial center of the propeller housing 38. A propeller 45 is vertically positioned in the housing 38 and its hub is fastened to the shaft 44.

Journal brackets 46, for the shaft 44, extend up from and are fastened to the base 28. A reversing electric motor 50, whose armature shaft 51 is detachably connected to the shaft 44, is secured to the supporting block 52, and the latter extends up from and is fastened to the base 28. An outlet pipe 53 extends from the wall 21 and has connected thereto the outlet valve 55, with the outlet nozzle 56.

A U-shaped angle iron 57 is fastened to the bottom wall of the basket 80, to be described. A heater pipe 58 is supported at the top end of the container 20 and is supplied with a flow of steam by means not shown.

An angle iron 65 is fastened to the flange 22.

An oblong shaped operating receptacle is designated in its entirety by the numeral 70, and comprises the oblong shaped vertical wall 71, the lower end of which bears on the flange 22, and is connected to the angle iron 65. An angle iron 72 is fastened to the upper part of the wall 71.

A directional relay 75 is provided for the electric motor 50. By means of the said relay the electric motor 50 can be automatically and intermittently rotated in reverse directions.

A basket for the objects to be dyed is designated in its entirety by numeral 80. The basket 80 comprises the bottom wall 81 with the perforations 82 and the extensions 83, extending from its bottom wall 81. The vertical oblong shaped wall of the basket is shown at 88 with the locking openings 89 extending therethrough. A pair of reinforcing strips 92, having the locking openings 93, are secured to the wall 88. The openings 93 are coaxial with their adjacent openings 89.

The cover of the basket 80 comprises the pair of identical members 95, which conform in shape to the wall 71 of the operating receptacle 70. To the top face of each member 95 is fastened the

angle iron 98, having the guide opening 99 extending through the vertical flange thereof.

Each of the members 95 of the cover has extending up therefrom the guide brackets 100 and 101, and the stop lugs 105. A locking bolt 108, having the handle 109, is provided for the curved end of each member 95. The bolt 108 extends through openings in the brackets 100 and 101, and the handle 109 is adapted to be positioned 10 between the stop lugs 105. The bolt 108 is adapted to engage the openings 93 and 89 for different levels or positions of the members 95, and may have extending therethrough the pin 108a.

At the adjacent ends of the members 95 of the 15 cover are indicated the pairs of guide and journal brackets 110 and the pairs of stop lugs 112. A pair of locking bolts 115 each having the handle 116 are supported in openings of the brackets 110.

20 A pair of guide strips 120, with the locking openings 121, are secured to the inner opposite faces of the longitudinal portions of the vertical walls 88 of the basket 80, and extend to the top of the receptacle 70. Openings 123 are indicated 25 in the wall 88 of the basket which register with the openings 121. The locking bolts 115 are adapted to lock with the different openings 121 and 123, to lock the members 95 at different levels. Also the lock bolts 115 function as hinge 30 pins to enable the members 95 of the cover of the basket to be swung open. To the upper ends of the guide strips is fastened the cross bar 125.

On the opposite sides of the receptacle 70, are 35 indicated the pair of box shaped guide posts, respectively comprising the members 130, 131 and the members 132, 133. A slide bar 134, is indicated in each of the members 130 and 132. At the upper end of each slide bar 134 is indicated a seat 135, in which the crossbar 125 is supported. 40 From the lower ends of the slide bars 134, extend the pins 136 and 136a.

An electric motor 140, is supported on the base 28. A pair of journal brackets 141, are supported on the base 28 adjacent to the electric 45 motor 140. A worm shaft 143, having the worm 145, is journaled in the journal brackets 141. The said worm shaft 143, is detachably fastened to the armature shaft of the electric motor 140, by means of the coupling 147. Journal pins 148 50 and 149, extend from the member 131. A worm wheel 155, is journaled in the pin 148 and has integral therewith the pinion 156. The worm wheel 155 meshes with the worm 145. A shaft 158 is journaled in the members 131 and 133, and has 55 fastened thereto at one end the spur gear 160, which meshes with the pinion 156. A pin 162 extends from the spur gear 160. A link 165 has one end pivoted on the pin 162, and its other end is pivoted on the pin 136. To the other end of 60 the shaft 158, is fastened the crank 168. A link 165a, has one end pivoted to the crank 168, and its other end is pivoted to the pin 136a.

A bracket 169, is fastened to the guide post member 130, which has pivoted thereto the operating arm having the members 170 and 171. An operating handle 172, extends from the member 170. A switch arm 173, extends from the operating arm and is insulated therefrom. Three terminals a, b and c, are carried on the bracket 169.

70 An operating lug 174, extends from the adjacent slide bar 134. Two stop lugs 175 and 175a extend from the guide post member 130. A wire 176, with the source of electric current 177, leads from the electric motor 140 to the terminals b 75 and c. A wire 178 leads from the electric mo-

tor 140 to the terminal a. The adjacent slide bar 134, with the basket 80, see Fig. 1, are indicated in their lower position. To raise the basket 80, the handle 172 is swung in the direction of the arrow A, until the member 170 strikes 5 stop lug 175 and the switch arm 173 contacts with the terminal b, which energizes the motor 140 to turn the latter. The slide bars 134 rise and the basket 80 is elevated. At the upper end of the stroke of the slide bars 134, the lug 174 10 contacts with the member 170 and the operating arm located in its neutral position indicated, in Fig. 1, and the electric current is opened and the electric motor 140 stops and the basket is in its upper position.

15 To lower the basket the handle 172 is swung in a direction opposite to the arrow A, and the switch arm 173 contacts with the terminal c. The electric circuit of the motor 140 is thereby closed and the basket is lowered and the lug 174 finally 20 contacts with the arm 171, and the operation is repeated.

To operate the apparatus, the covers 95 of the basket 80, are swung up and dye liquor poured into the dye liquor reversing container 20. The 25 basket 80 is then positioned at the required level by energizing the electric motor 140. This is accomplished by swinging the handle 173 to close the electric circuit between the wires 176 and 178. When the motor 140 turns, rotation is imparted 30 to the spur gear 160 and thereby the links 165 and 165a, vertically move the slide bars 134. When the latter rise, they raise the crossbar 125 and thereby the basket 80 is raised to the required level.

35 The bolts 108, of the members 95 of the cover of the basket, are disengaged from the wall 88 and the strips 92, after which said covers can be swung open. The basket 80 is then packed with the articles to be dyed and the covers are closed 40 and locked in place. The covers are locked at the required level by means of the locking bolts 115, after the electric motor 140, has been stopped.

When the electric motor 50 is energized, propeller shaft 44, with its propeller 45, are turned 45 in reverse directions at proper intervals, by the coaction of the directional relay 75. By this means the dye liquor in the container 20 is forced at proper intervals of time in opposite directions through the perforations 82 of the bottom wall 50 81 of the basket 80, and penetrate the articles in said basket. The dye liquor then returns to the container 20 in cycles as required to quickly and efficiently dye said articles packed in the basket 80. It will be noted that when, for example, the 55 dye liquor is forced from the chamber 41, it is under pressure by the effects of the propeller 38, when it enters the textiles in the basket 80. The dye liquor then flows to the openings 82 over the chamber 40. At this point the propeller 45, by its 60 suction effect, draws the dye liquor into the chamber 40.

When the rotations of the propeller 45 are reversed, the dye liquor is forced from the chamber 40 into the textiles under pressure and drawn into the chamber 41 with a suction effect from the propeller 45.

65 At the required times the said articles are removed from the said basket, and the latter is charged again with articles to be dyed. It will be noted, that the dye liquor enters the articles to be treated from the top and bottom sides.

To drain the tank 20, the valve 55 is opened. Various modifications may be made in the in- 75

vention and the present exemplification is to be taken as illustrative and not limitative thereof.

Having described my invention I claim:

- 5 1. In a dyeing apparatus the combination of a container for a dye liquor, an operating receptacle above and connected to said container, a basket in said receptacle having perforations therethrough, said basket adapted to have articles to be dyed packed therein, a cover detachably hinged and bolted to the basket, a pair of guide strips extending up from the basket, a crossbar connected to the upper ends of said guide strips, a slide bar adjacent each of the 10 sides of said receptacle, means to vertically move said slide bars, said slide bars contacting with the ends of the crossbar at the upper ends of their strokes to locate the basket at different levels and means to circulate the dye liquor from 15 the container through the articles in the basket.
